UNITED STATES PATENT OFFICE.

JOHN J. KEVILLE, OF LEOMINSTER, MASSACHUSETTS.

ORNAMENT FOR PERSONAL WEAR.

Application filed June 30, 1926. Serial No. 119,722.

This invention relates to a means for holding in position on the hair or garment an ornamental device of celluloid or other material. It is an improvement on the well known barrette or clasp which turns and twists even if it does not fall off.

The principal objects of the invention are to provide a holding means to grip the hair or dress throughout a wide area and especially along two lines at a distance from each other, so that the article will stay in position on the garment or other material and face the front at all times; and to provide a construction that can be made of a single piece of celluloid or other spring material and which can be fastened and unfastened with a very slight motion and will be sure to hold after it has been fastened.

Reference is to be had to the accompanying drawings in which

Fig. 1 is a front view of a hair ornament constructed in accordance with this invention;

Fig. 2 is a rear view of the same;

Fig. 3 is a sectional view on the line 3—3 in Fig. 2; and

Fig. 4 is a rear view of another form in which this invention can be carried out.

Referring to the first three figures, the ornament is shown in the form of a celluloid or metal piece 10 having a representation of a flower or the like on the front. This can be of any desired shape and character and in fact of any material.

On the back is secured or fixed in place, a projection 11 which has a round hole through it from top to bottom which constitutes a hinge as will appear. On the opposite side there is a post 12 having a groove 13 at its outer surface.

It will be noticed that the rear of the ornament 10 is rounded in this case. It is provided with a part of a spherical surface so it slants away from the center in all directions but always on the same curve. This results in the post being located on a slant even if perpendicular to the surface. In fact this is emphasized and the post is set at a slightly greater angle for a purpose that will appear.

The holding device in this instance consists of a ring 20 of round celluloid or metal wire connected together at its ends so as to be an endless construction. In this form the ring is perfectly circular and it is fitted in

the hinge piece to swing thereon from open to closed position. When in closed position it will engage the top of the post on the other side and it can be forced from the top into the groove without difficulty. This groove is located in such relation to the rounded rear surface of the ornament that it forces the ring against that surface throughout the length of the ring. The pivot hole on the other side is also located so that the ring comes into contact with this surface.

On account of the spherical nature of this surface, there is a slant all around under the ring which assists in holding the device clamped on the hair or garment. As a matter of fact it is found that this holds the hair or other material on which it is placed throughout the length of the circle and naturally each hair passes through the device and is held at two places a distance apart. For that reason it is particularly useful as an ornament in the hair. Only a short length of hair is required to hold it in position. It does away with the ordinary devices which are used to fasten short hair, which have proved to be practically useless at the present time.

It is not limited to be used on hair, however, and it can be used to fasten two parts of a garment together, particularly if it is of fine material. It also can be used to attach ornaments on garters and buckles and other ornaments on shoes.

It will be noted that the ring is located entirely within the surface of the article or buckle to which it is applied so it will not show from the front. It serves only as a fastening device and not a part of the ornament to be seen.

In Fig. 4 the same principles are involved except that the ornament 40 or buckle is flat on the back and that on account of the shape which the ornamental part has, the fastening device 30 is shown in the form of a square with rounded corners instead of a ring.

It will be understood of course, that the invention is not limited as to the shape of this fastening member and it will be given whatever shape is necessary to provide the most efficiency in the holding means for the particular shape of the article to which it is to be applied.

Although I have illustrated and described

only two forms of the invention I am aware of the fact that other modifications can be made therein by any person skilled in the art without departing from the scope of the invention as expressed in the claims. Therefore, I do not wish to be limited in these respects, but what I do claim is:—

1. As an article of manufacture, an ornament for personal wear comprising a plate 10 having its front surface ornamented, provided at opposite points on the back with a projection having a passage all the way through it and a post having a groove on its outer side, said groove and opening being located substantially at the same level as the surface of the back, and a ring of yielding material pivoted in said perforation and of such width that it will have to be distorted a little to bring its opposite 15 edge over the post and into the groove, whereby it will be held in contact with the back throughout its length and it will hold the hair or garment on which it is placed on

two lines on opposite sides of the diameter connecting the projection and post. 25

2. In an ornament for personal wear, the combination of a plate convex on the back, a fastening means therefor comprising a ring pivoted on one side of the back at a point closely adjacent to the convex surface, and means for temporarily holding the opposite side of the ring on the opposite side of the back and close to it all around for the purpose described. 30

3. In an ornament for personal wear, the combination with a plate having a back in the form of part of a sphere and provided with a projection and a grooved post diametrically opposite at the edges thereof on the back, of a circular ring pivoted in said projection and adapted to be sprung into place in the groove in the post for holding it on the hair or garment. 35 40

In testimony whereof I have hereunto affixed my signature.

JOHN J. KEVILLE.
